INVENTOR
F. H. WILKEY
BY Murray Co.
ATTORNEYS

UNITED STATES PATENT OFFICE.

FRANK HENRY WILKEY, OF CAMP POINT, ILLINOIS.

HARROW SEAT.

Application filed April 9, 1923. Serial No. 630,850.

To all whom it may concern:

Be it known that I, FRANK HENRY WILKEY, a citizen of the United States, and a resident of Camp Point, in the county of Adams and State of Illinois, have invented a new and useful Improvement in Harrow Seats, of which the following is a full, clear, and exact description.

My invention relates to improvements in harrow seats, and it consists in the combinations, constructions, and arrangements herein described and claimed.

An object of my invention is to provide a harrow seat of the character described which the operator may sit upon for a relatively long time without becoming tired.

A further object of my invention is to provide a device of the character described in which means is provided for resting the seat upon two or more sections of the spike harrow or drag, so that the weight of the person upon the seat will be distributed upon the several sections.

A further object of my invention is to provide a device of the character described in which means are provided for adjusting the position of the seat relative to the sections to suit the requirements of the particular person using the implement.

A further object of my invention is to provide a device of the character described which greatly facilitates the operation of a section harrow, since each of the sections is at all times maintained at an equal distance from one another, and therefore cannot jam or separate by contact with unusual formations in the ground, such as ridges or cavities.

A further object of my invention is to provide a device of the character described which may be readily applied to the ordinary spike harrow or drag, without the use of special tools.

Other objects and advantages will appear in the following specification, and the novel features of the invention will be particularly pointed out in the appended claims.

My invention is illustrated in the accompanying drawings, forming part of this application, in which

Figure 1 is an end elevation of an embodiment of my invention,

Figure 2 is a front elevation of the mechanism illustrated in Figure 1, each end thereof being broken away, 55

Figure 3 is an enlarged sectional view substantially along the line 3—3 of Figure 1,

Figure 4 is an enlarged fragmentary view of intersecting portions of the seat supporting structure,

Figure 5 is a rear elevation of a modified form of my invention,

Figure 6 is an enlarged top plan view of a portion of the mechanism shown in Figure 5, and

Figure 7 is a side elevation of the mechanism illustrated in Figure 6.

In carrying out my invention, I make use of the ordinary type of section harrow 70 having spikes 2 secured to members 3, which members are pivotally supported upon parallel supporting members 4. A lever 5 is provided by means of which the parallel members 4 may be moved longitudinally of one another to alter the angular position of the spikes 2. A lower bar or rod 6 is connected with each of the members 3 and at its forward end by means of a hook 7 to a draw bar 8. In the present preferred embodiment of my invention, I show two of the sections indicated at A and B in Figure 2. A single draw bar 8 is employed at all times. The draw bar 8 is connected to the rod 6 of each of the harrow sections, as 85 illustrated in Figure 1.

My improved harrow seat consists in a pair of substantially S-shaped rigid bars 9 having a seat 10 at the upper end thereof, and a pair of arms 11 pivotally mounted to the bars 9 at 12. An intermediate brace 13 is disposed between the bars 11 (see Figure 2). The lower ends of the bars 11 are secured by means of rivets 14 or the like to an angle bar 15, which angle bar is sufficiently long to rest upon the upper of the parallel supporting members 4 as shown in Figure 1.

The angle bar 15 is provided with a pair of shiftable U-shaped members 16 (see Figure 3) bolted on the under side thereof by means of a stub shaft 18 and a nut 19. The stub shaft 18 is projected through one of a plurality of holes disposed in the angle bar

15, thereby permitting adjustment as to the position of the U-shaped member 16. This U-shaped member 16 is permitted to straddle the upper of the parallel supporting bars 4, as shown in Figure 3, and therefore serves as a means for positioning the sections A and B from movement laterally toward or away from one another.

A seat elevation adjusting bar 20 is pivotally mounted at 21 to the S-shaped bars 9 (see Figure 1). The outer end of the adjusting bar 20 has a plurality of openings 22 therethrough. These openings are arranged for engagement selectively with a bolt 23 projected through a pair of lug members 24 secured to the angle bar 15 by means of bolts 25.

A foot rest 26 is adjustably supported upon the S-shaped bar 9 by any well known means (not shown). The draw bar 8 is provided with an upwardly extending substantially Y-shaped member 27, the branches 28 of which are pivotally mounted to the lower end of the parallel S-shaped bars 9.

From the foregoing description of the various parts of the device, the operation thereof may be readily understood. It will be apparent from an inspection of the drawings that I have provided in my improved harrow seat a most comfortable support. The ordinary manner for employing a harrow or drag is to place a plank across the top of the harrow and to stand thereupon. This procedure is dangerous and tiring to say the least. By the use of my improved device, a comfortable seat is provided that may be adjusted to suit the particular requirements of the person using the harrow, that is, the bars 20 may be adjusted relative to the angle bars 15 so that the seat 10 may be moved forward or toward the rear of the harrow and thus adjust the weight of the person upon the seat so that it will cause a uniform contact of the harrow with the ground and thereby preclude the tilting of the forward or the rear end of the harrow as is common in the ordinary type of fixed harrow seat.

One of the important features of my present invention is that while in use the sections A and B do not move toward one another or move away from one another even though the ground over which the harrow is passed may be uneven and present repeated ridges, cavities, or the like, which would tend to misguide the ordinary type of harrow where two or more harrows are used on a single draw bar.

In Figures 5, 6, and 7, I have shown views of a modified form of my invention in which I may employ more than two sections. In the form shown in Figure 5, I employ three sections, but it is apparent that other sections may be added at the will of the operator.

The structure shown in Figure 5 differs somewhat from the structure shown in the preferred form of the invention in that the equivalent of the angle bar 15 is broken into two parts 29 and 30 and pivotally connected with one another at 31 (see Figures 6 and 7).

In place of using a single angle iron for the members 29 and 30, I employ pairs of angle bars 32 and 33, the bars 32 being clamped in fixed relation to the bars 33 by means of spacing members 34 fixed to the angle irons 32 and 33.

Members 16' are supported as shown in Figure 5, one adjacent each of the outer ends of the joined sections 29 and 30, and one directly below the pivotal connection 31 (see Figure 6).

These members are arranged to engage with the upper of the parallel bars 4 of three harrows indicated generally at 35, 36, and 37. The bar 15, with the seat supported thereupon, is then placed upon the connected parts 29 and 30 so that the V-shaped members 16 straddle the spacing members 34 (see Figure 5), whereupon the device is ready for use.

The operation of this modified form is substantially the same as in the preferred form. The harrows remain at all times at a spaced distance from one another, being free to move vertically without changing their lateral relation with one another.

Obviously, my improved harrow seat may be applied to any make of harrow, and I do not wish to be confined to the particular construction of harrow disclosed in the foregoing specification, which disclosure is illustrative of one particular embodiment of my invention.

I claim:

1. The combination with a plurality of harrows arranged in lateral alinement, and a draw bar for said harrows, of a seat supporting member supported at one end on said draw bar, a cross bar carried on said harrows transverse thereto, and adjustable supporting means secured at one end to said seat supporting member and at the opposite lower end to said cross bar.

2. The combination with a plurality of harrows arranged in lateral alinement, and a draw bar for said harrows, of a seat supporting member supported at one end on said draw bar, a cross bar carried on said harrows transverse thereto, adjustable gripping means carried by said cross bar on the under side thereof and arranged to engage with said harrows, thereby to limit the lateral movement of said harrows relative to one another, and adjustable supporting means secured at one end to said seat supporting member and at the opposite end to said cross bar.

3. The combination with a plurality of

harrows arranged in lateral alinement, and thereof and arranged to engage with said harrows, thereby to limit the lateral movement of said harrows relative to one another, and adjustable supporting means secured at one end to said seat supporting member and at the opposite end to said cross bar.

5 mounted on said seat supporting member, a cross bar carried on said harrows transverse thereto, adjustable gripping means carried by said cross bar on the under side

FRANK HENRY WILKEY.
